[57] CLAIM

The ornamental design for a clock, as shown and de-
scribed.

DESCRIPTION

FIG. 1 is a front elevational view of a clock showing
our new design;

FIG. 2 is a rear elevational view thereof;

FIG. 3 is a top plan view thereof;

FIG. 4 is a bottom plan view thereof; and

FIG. 5 is a right side elevational view thereof, the left
side being a mirror image.

FIG. 1

FIG. 2

FIG. 3

FIG. 5

FIG. 4
